PAPER MONEY COUNTING MECHANISM

Frank J. Callen, Clanton, Ala.

Application February 20, 1936, Serial No. 64,975

1 Claim. (Cl. 271—27)

This invention relates to a machine or mechanism for counting paper money.

It is aimed to provide a novel means minimizing the danger of paper money or bills sticking together and a plurality being erroneously counted as one.

It is further aimed to provide a novel structure wherein the bills are removed by suction, conveyed through a distance sufficient to enable adhering bills to become dislodged and then to be stripped.

It is still further aimed to provide such a structure wherein the counted bills are filed or stacked.

15 Various additional objects and advantages will become apparent from a consideration of the description following taken in connection with accompanying drawings illustrating an operative embodiment.

20 In said drawings:—

Figure 1 is a view of the apparatus in side elevation;

Figure 2 is a front end elevation of the apparatus;

25 Figure 3 is a longitudinal sectional view through the stacking drawer and its mounting;

Figure 4 is a detailed section taken on the line 4—4 of Figure 1;

Figure 5 is a detailed vertical sectional view 30 through part of the apparatus;

Figure 6 is a horizontal sectional view taken on the line 6—6 of Figure 5;

Figure 7 is a detailed section taken on the line 7—7 of Figure 1; and

35 Figure 8 is a detailed section taken on the line 8—8 of Figure 1.

Referring specifically to the drawings wherein like reference characters designate like or similar parts, 10 designates a suitable stand or support 40 having bearings 11 in which a shaft 12 is journaled and which shaft is adapted to be manually turned through manipulation of a crank 13.

A drum or wheel is provided at 14. Such drum or wheel 14 has a hub 15 keyed to the shaft 45 12 as at 16 so as to rotate therewith. A casing 17 is rigid with the hub and divided by the latter into four (4) non-communicating compartments or chambers 18 in each of which a suction fan 19 is mounted, being driven for instance by an electric motor 20. Suitable connections are made 50 with a source or sources of electric energy to continuously drive each of the motors 20 and associated fans 19.

Extending from each chamber 18 rigid with 55 the casing 17 and hub, is a hollow tube or spoke

21. Said spokes 21 at their outer ends are rigidly connected to a ring or rim 22 at the outer surface or periphery of which as the tubes 21 are opened.

The drum or wheel is adapted to move clockwise to convey bills or paper currency or the like 23 from a stack and which bills are adapted to be stripped from the periphery of the rim 22 by a chute 24, preferably of channel shape as shown in Figure 4, and curved, down which chute, the bills or the like fall by gravity and are caught in slidably removable drawer 25 carried by a frame 26, the chute and frame being supported in any desired manner as by means of brackets 27 connected thereto and also connected to the frame 10. A displaceable spring member 28 on 15 the frame 26, normally prevents displacement of the drawer 25.

The bills or other articles to be counted are disposed within a receptacle 29, resting on a vertically movable false bottom 30 and normally 20 resting on an inwardly extending flange 31 at the lower edge of receptacle 29. In addition, a closure 32 is provided at one end of the receptacle for lowering to permit the bills 23 to be replenished. This closure is secured in place 25 by a spring hinge at 33, the spring urging the closure to and normally maintaining it in closed position. A bracket 34 supports the receptacle 29 on frame work 10.

As suction through the tubes 21 is adapted to 30 remove a bill from the pile as the wheel or drum rotates, a projection 35 extends inwardly from the rim 22 adjacent each tube 21 such projections are adapted to engage an actuating member 36 of a conventional counter 37 suitably supported on the frame work 10, such counter thus being operated every time one of the projections 35 engages member 36 and thus four 35 times for each revolution of the rim, and being designed to count up to any desired number, for 40 instance 50, which is the number of bills usually packaged in a bank.

In the operation of the device, handle 13 is turned to rotate the wheel or drum. While one hand is used for the foregoing purpose, the 45 other hand presses upwardly on the false bottom 30 so that as each tube 21 passes over the pile of bills 22, it will by suction remove the uppermost bill maintaining it by such suction in contact with the periphery of the rim 22 until the 50 bills reach the chute 24 which strips the bills from the rim 22 so that they fall or slide down the chute 24 into the drawer 25. During such rotation of the wheel drum, it is clear that the 55 motors 20 are energized and that the suction 55

fans 19 are in operation. When the operator has removed the desired number of bills as indicated by the counter 37, for instance 50, he stops turning the crank 13 and removes or bundles the counted pile of bills in the drawer 25. It is clear that since the bills travel a substantial distance to the wheel while exposed, any bills adhering to the bills in direct contact with the periphery of the drum, will fall therefrom.

10) Various changes may be resorted to provided they fall within the spirit and scope of the invention.

I claim as my invention:—

A structure of the class described comprising

a rotating element having a rim of annular form, a hub having compartments therein, hollow spokes leading from the hub and being in communication with the compartments and open at the periphery of the rim, means for creating a suction within the compartments and through the spokes serving to cause articles to adhere to the periphery of the rim, a shaft for said hub, and a plate closing one side of the hub and mounting said means for creating a suction, said 10 chambers being in communication with the atmosphere through said hub and plate.

FRANK J. CALLEN.
